UNITED STATES PATENT OFFICE.

ANNA MILEY, OF LOS ANGELES, CALIFORNIA.

SPIRAL THUMB-TACK.

1,189,604.

Specification of Letters Patent.

Patented July 4, 1916.

Application filed December 13, 1915. Serial No. 66,618.

To all whom it may concern:

Be it known that I, Mrs. ANNA MILEY, a citizen of the United States, residing at Los Angeles, in the county of Los Angeles and State of California, have invented new and useful Improvements in Spiral Thumb-Tacks, of which the following is a specification.

My invention relates to an article of manufacture and in particular to a spiral thumb tack.

It is an object of this invention to construct a tack which has the appearance of a normal thumb tack and which serves to support photographs, pictures, cards, and the like. The tack consists of a head made of metal plate, to which a length of spring wire is attached in any suitable manner and which, after a suitable number of coils, ends in a sharpened point.

In the accompanying drawings which form a part of this specification, I have shown an embodiment of my invention and in which:

Figure 1 shows the improved thumb tack attached to a wall, or the like, and a card or photograph held by said tack. Fig. 2 is a front elevation of the tack. Fig. 3 is a perspective view thereof, looking from the lower side. Fig. 4 is a vertical cross-section through the center thereof. Fig. 5 is a plan view of the under side thereof.

The improved tack is made of a circular head 10 made of thin metal plate. The same is preferably slightly convex on its upper face. A length of spring wire 11 is suitably attached by soldering or any other convenient method to the under face of said head. The length of wire 11 is bent to form two circular coils 12 of a size corresponding to the periphery of the head, or slightly smaller, so that said coils will not be visible when the tack is viewed from the top.

It is obvious that the number of coils is immaterial, and, if desired, more than two

coils may be formed, but ordinarily two coils are sufficient for the purpose for which the tack is intended. These coils are in close relation to each other, so that a photograph or card, and the like, when inserted between the coils, as shown in Fig. 1, will be securely held in position by the frictional contact of the wire. The lower coil is bent so that the end portion 13 extends to the center of the coil, from which a vertical 55 sharpened portion 14 extends downwardly to form the end.

From the foregoing description, the use of the tack will be obvious. The tack is fastened to any suitable object, such as a 60 wall, or the like, by pressing on the head, which will force the sharpened end into the wall. A card, or the like, may be inserted between the coils, where the same will be held securely in position by the frictional 65 contact of the latter.

It is thus seen that I have devised an improved thumb tack consisting of two parts,—the head and the length of wire, which, when viewed from the top, has the 70 appearance of a normal thumb tack and may be used as such, but which serves to frictionally suspend photographs, cards, and the like.

I claim:

A tack consisting of a head of metal plate, a length of spring wire attached to the under face thereof, said spring wire forming a plurality of helical coils having a diameter not to exceed the diameter of 80 the head, said coils being close together and adapted to frictionally hold cards and the like between them, the lower coil of said wire being bent toward the center of the last coil and projecting downwardly there- 85 from to form a sharpened point.

In testimony whereof I have signed my name to this specification.

MRS. ANNA MILEY.
